UNITED STATES PATENT OFFICE.

BERT H. HITE, OF MORGANTOWN, WEST VIRGINIA.

CORNET.

SPECIFICATION forming part of Letters Patent No. 412,753, dated October 15, 1889.

Application filed July 9, 1889. Serial No. 316,980. (No model.)

To all whom it may concern:

Be it known that I, BERT H. HITE, a citizen of the United States, residing at Morgantown, in the county of Monongalia, State of West Virginia, have invented certain new and useful Improvements in Cornets and Similar Instruments, of which the following is a specification.

My invention relates to an improvement in cornets and similar instruments involving the use of valves to produce certain tones, and while it is particularly applicable to the cornet, and so described in this specification, it will be found that its essential features may be used successfully and profitably upon all instruments of a like nature.

The purpose of the invention is, first, to provide for the easier production of "valve-tones," so called; secondly, to produce an instrument which, having all the necessary effectiveness, shall be cheaper in construction and lighter and more convenient to handle, and, thirdly, to effect such an improvement in the valves proper as to adapt them to provide, with the crooks and valve-slides, whether the valves be up or down, a uniform serpentine passage for the wind without any sudden bends, such as are found almost universally in instruments of a similar character heretofore produced.

My invention has for a further object improvements particularly applicable to the cornet hereinafter described.

To these ends my invention consists in a cornet or similar instrument the valves of which are made in horizontal section substantially of the outline of the sector of a circle provided with one curved aperture running from side to side parallel with the outer curve of the sector, and two curved apertures in line above the first named, each running transversely through the valve-opening upon the curved rear part of the valve and the contiguous flaring side. Three such valves are usually provided and sustained in the casing, having a proper internal configuration to receive them, and having intermediate walls and the necessary perforations to afford communication from one valve to the other and

from the respective valves to the respective crooks and valve-slides.

My invention further consists in so constructing the instrument that the various crooks and valve-slides shall open into the casing inclosing the valves in the same plane, usually horizontal, in such manner as to afford communication through the holes in the partition directly with the valve-holes of the adjoining valves, and not, as has heretofore been common, through interposed straight short tubes.

My invention further consists in details of construction and arrangement of parts, substantially as hereinafter described.

In the drawings, Figure 1 is a side elevation of a cornet constructed in accordance with my invention. Fig. 2 is a bottom plan view with the lower cap removed from the valve-shell. Fig. 3 is an enlarged elevation of the valves detached. Fig. 4 is a similar elevation viewed in the opposite direction. Fig. 5 is an enlarged perspective view of the valve-shell removed with the valves introduced.

The arrangement of wind-passage, except as to the following modification, may be as usual, and the proper valve-crooks A B C employed for the usual purpose. Instead, however, as heretofore, of having the valves of cylindrical form, incased in cylindrical shells, communicating with each other through short straight tubes, and having the valve-crooks communicating with the separate shells, I provide the casing D, separated into compartments *t't' t''*, internally sector-shaped, each compartment having the openings shown, and having intermediate partitions, which may be permanent or adjustable, and are also perforated. The perforations throughout the shell and partitions are in the same horizontal plane.

The valve-casing D may be surmounted with tubes s, to receive the valve-stems, which latter are surrounded by a spring and otherwise constructed and operated in the usual manner. The valves are substantially sector-shaped in horizontal section, and arranged so that the inner flat sides of the

valves E and E'' shall be contiguous to the flat sides of the intermediate valve E', the curve of the latter being thus opposite to that of the two former. Each valve is provided with the longitudinal curved passage *r* in its lower part, and above the latter with the two curved passages *p*, formed transversely through the valve, as shown.

It is apparent from the foregoing description that when, under the tension of the springs, the valves are in their uppermost position a continuous wave-like wind-passage exists through the series of valves from the crook *q* to the crook *q'*, the valve-crooks A, B, and C being cut off from communication. It is also apparent that if the middle valve alone is depressed a continuous smooth wind-passage exists from the crook *q* through the curved passage *r* in the valve E'', through the passage *p* in the valve E' into the valve-slide C, thence through the curved passage *r* in the valve E and out into the crook *q'*. If the valve E'' alone be depressed, it will be apparent that a continuous passage is formed, including the valve-crooks B. If the valve E be depressed, a continuous passage is produced including the valve-crooks A. If the valves E and E'' be depressed, a continuous passage will be formed including the valve-crooks A and B, and so on throughout the series.

It is to be noted as an important feature of my invention that whether none, either, any two, or all of the valves are down the wind-passage through the instrument will present a continuous serpentine line, the curve being in no instance shorter than a simple return bend. The instrument is absolutely "clear-bore," and the tone is therefore better. The valve-tones, not involving any objectionably short curves, are approximately as easy to produce as the open-tones.

Among the many advantages of my construction may be mentioned the following: The valve-slides, being all at the bottom of the valves, produce a good hand-hold. The valves, being alike, are interchangeable. The stroke is as short as it is possible to make it on a piston-valve. The valves are necessarily lighter than those formerly made and present less wearing-surface than those heretofore made, and the action is therefore much lighter. Finally, it is to be observed that when any two adjacent valves are down, the wind, having passed out into the valve-slide of one valve, returning passes directly out into the valve-slide of the adjacent valve—an operation not possible with any other form with which I am acquainted.

In Fig. 2 I have illustrated a desirable construction of the middle valve-slide C for the purpose of lengthening it, which consists in having the tube straight at *o*. It is clear that this feature is capable of alteration. The valves may be removed from the shell D by providing a cap *n* at the lower end of

the latter, Fig. 1, and screw-jointing the valve-stem, as shown in Fig. 3. Instead of this construction the sector shape of the valve-chamber may be continued to the top of the tubes *s*, the caps being applied thereto and sustained with thumb-screws. Such details of construction, as well as the adaptation of the essential parts of the invention hereinafter claimed to instruments of various kinds, are matters within the province of the skilled mechanic, and my invention is not limited thereto.

I have shown and described the valves as sector-shaped in horizontal section, and I find that the near approach to this outline presents important advantages. The valve-stem is secured at a point close to the apex of the sector, and the three stems are therefore closer together, offering a more convenient arrangement of the valve-buttons to receive the fingers in playing. It is to be noted, however, that my invention is not limited to a strict conformity with the description in this regard, as it is apparent that a departure from the perfect sector shape, preserving, however, the prescribed arrangement of apertures and slide-openings, and having substantially this shape, will produce a result approximately satisfactory.

What I claim as new, and desire to secure by Letters Patent, is—

1. A valve for cornets and similar instruments, made substantially sector-shaped and provided with apertures, as described.

2. A valve for cornets and similar instruments, having a longitudinal curved aperture and two transverse curved apertures in a horizontal plane different from the other, as described.

3. A cornet or similar instrument provided with valves substantially sector-shaped, each having a longitudinal curved aperture, and two transverse curved apertures in a horizontal plane different from the other aperture to provide a continuous curved passage for the wind in producing all tones, substantially as described.

4. A cornet or similar instrument having all its valve-shell openings in the same plane and communicating with the crooks, as described.

5. A cornet or similar instrument having a valve-shell with apertures in the same horizontal plane, valve-slides communicating with the apertures in the manner described, and valves within the valve-shell provided with the longitudinal and transverse curved passages described, affording communication, as set forth.

6. A cornet or similar instrument comprising the usual wind-passage for open-tones and having a valve-shell divided into communicating compartments by perforated partitions, valves moving within said compartments, each provided with three curved pas-

sages in two horizontal planes, and valve-slides in the same horizontal plane communicating with the curved passages in the valves through the perforations in the shell, 5 all as set forth.

7. In a cornet or similar instrument, substantially sector-shaped valves and valve-

stems joined to the valves near their apexes, as described.

BERT H. HITE.

In presence of—
E. SHISLER,
W. T. KERN.

It is hereby certified that in Letters Patent No. 412,753, granted October 15, 1889, upon the application of Bert H. Hite, of Morgantown, West Virginia, for an improvement in "Cornets," errors appear in the printed specification requiring correction, as follows: In line 42, page 1, the word "valve-opening" should read *valve, opening*; in lines 25 and 27, page 2, the word "valve-crooks" should read *valve-crook*; and that the said Letters Patent should be read with these corrections therein that the same may conform to the record of the case in the Patent Office.

Signed, countersigned, and sealed this 22d day of October, A. D. 1889.
